UNITED STATES PATENT OFFICE

FRANK A. KING, OF DENVER, COLORADO

TUNNELING MACHINE

Application filed July 29, 1929. Serial No. 381,715.

This invention relates to improvements in tunneling machines.

In the installation of sewers, water mains and other underground openings and conduits, it is customary to dig a trench from the surface of the ground and after the conduits have been put in place or constructed, the trench is filled in. This practice makes it necessary to destroy the paving of streets and to obstruct traffic during the period that the construction takes place. When trenches are cut in the manner above intimated, it oftentimes interferes with the foundations of buildings, as it removes or destroys the lateral support whenever these trenches extend below the foundations.

It is the object of this invention to produce a machine by means of which a tunnel of any desired size can readily be cut through the ground without interfering with the surface and therefore by means of this machine, it is possible to install or build a sewer or water main underneath the street without interfering with the traffic and also, for reasons that will become apparent as the description proceeds, without interfering with the foundations of any buildings or other structures adjacent to the path of the tunnel.

This invention, briefly described, comprises a machine having a shield of the size and form of the unfinished tunnel. An open frame whose outside shape and dimensions is such that it will fit the inside of the shield is located within and connected to the latter by means of a plurality of screws which have threaded connections with nuts secured to the front of the shield and whose rear ends are rotatably connected with the frame. Means are provided for simultaneously rotating the screws for the purpose of moving the shield forwardly with respect to the frame. I also provide a plurality of form members that are put in place directly back of the frame and which hold the concrete in place and determine the inside shape and size of the opening. In

addition to the above, I provide a plurality of retaining plates that can be put into place between the frame and the front edges of the forms after the concrete has been put in place and which serve to hold the concrete while the frame is moved forwardly so as to provide space for another form section.

Having thus briefly described the invention, the same will now be described in detail, and for this purpose reference will be had to the accompanying drawings in which the preferred embodiment of the invention has been illustrated, and in which:

Fig. 1 is a longitudinal vertical section through a tunnel showing my improved machine in place therein, the means for pouring the concrete mixture being shown in dot and dash lines;

Fig. 2 is a vertical transverse section taken on line 2—2, Fig. 1;

Fig. 3 is an end elevation of the front end of the shield looking in the direction of arrow 3, Fig. 1, a portion being broken away to better disclose the construction;

Fig. 4 is a section taken on line 4—4, Fig. 3, and shows the manner of securing the nut to the shield;

Fig. 5 is a section taken on line 5—5, Fig. 2;

Fig. 6 is a section taken on line 6—6, Fig. 5;

Fig. 7 is a section taken on line 7—7, Fig. 1, and shows the parts to an enlarged scale;

Fig. 8 is a section taken on line 8—8, Fig. 7, and shows the manner of connecting the retaining plates to the forms;

Fig. 9 is a bottom plan view of the latching members employed for securing the forms together at the top;

Fig. 10 is a section taken on line 10—10, Fig. 9;

Fig. 11 is a section taken on line 11—11, Fig. 1;

Fig. 12 is a longitudinal vertical section through the tunnel showing the conveyor which is employed for removing the muck;

Fig. 13 is a section taken on line 13—13, 90

Fig. 12, and shows the power take-off for operating the conveyor;

Fig. 14 is a section taken on line 14—14, Fig. 15;

Fig. 15 is a section taken on line 15—15, Fig. 14;

Fig. 16 is a section taken on line 16—16, Fig. 14;

Fig. 17 is a section showing the shaft coupling members separated; and

Fig. 18 is a fragmentary view showing the conveyor in collapsed position.

In the drawings reference numeral 1 represents the ground through which the tunnel is being built and 2 the concrete lining of the finished tunnel.

The tunneling machine consists of a shield 3 which is made from sheet steel of suitable thickness. The shield is bent into the shape desired for the unfinished tunnel opening and is held in shape by means of the two reenforcing members 4, which are formed from I-beams as shown in Figs. 1 and 4. The reenforcing members as well as the plates, are formed from several sections. The several sections of the reenforcing members have been designated by letters A and B, while the plate sections have been designated a, b and c. The lower section A of the reenforcing members is quite sharply curved compared to the sections B and these sections have their adjacent ends provided with flanges 5 that are connected by means of bolts 6 so that the shield may be taken apart at these points. The upper ends of the reenforcing sections B are connected with a transverse bar 7 which is located a short distance below the upper end of the shield. The shield section c has inwardly bent flanges 8 that are adapted to rest on the upper ends 9 of the reenforcing members and is secured between the reenforcing members and the bar 7 by means of bolts 10. In the example shown the shield has the form of an ellipse, which is believed to be the most suitable form for tunnels of ordinary size, but this machine is equally well adapted for tunnels of any other desired cross section. Located between the two reenforcing members 4 are lugs 11, that are secured in place by means of bolts or rivets 12. These lugs are provided with removable caps 13 that are held in place by means of bolts 14. The lugs 11 and the caps 13 have complementary semi-circular recesses that cooperate to form a circular opening for the reception and clamping of the cylindrical portion 15 of the elongated nuts 16. The cylindrical part 15 is provided at each end with shoulders that hold the nut against longitudinal movement and that portion of the inside opening corresponding to the cylindrical part 15 is threaded and adapted to be engaged by a screw 17 in the manner shown in Fig. 4. Extending forwardly from the cylindrical part 15 is a tubular portion 18 that serves as a

housing for the screw and protect the latter against injury from falling dirt during the excavating operation. The rear ends of screws 17 extend into housings 19 that are carried by the frame 20 and each screw is provided with a worm gear 21, which is engaged by a worm 22 carried on the lower end of shaft 23. These shafts extend upwardly to a gear casing 24 and have their upper ends provided with bevelled gears 25 that cooperate with similar gears on the lower ends of shafts 26, whose upper ends extend into the gear case 27 to which reference will herein-after be made. The shafts 23 and 26 are preferably enclosed in tubular housings like those indicated by reference numeral 28 in Fig. 11. These housings serve to protect the shaft against dirt and also make it possible to more readily keep dirt from entering the different gear casings. The connecting bar 7 has attached to it two guide bars 29 that extend rearwardly and pass through openings in the frame 20. The rear ends of guides 29 are connected by means of a yoke member 30 which has an opening through which the cylindrical housing 31 extends in the manner shown in Fig. 11. Secured to the connecting bar 7 midway between the guides 29, is a bar 32 that has the greater portion of its length threaded in the manner indicated at 33. The threaded portion of bar 32 extends through a tubular nut 34, one end of which is provided with threads that cooperate with the threads on the bar. The other end of nut 34 has a radial flange 35 which extends over the stationary part 36 of the gear casing and is separated from the latter by a washer 37. Part 36 of the casing has a rearwardly extending tubular portion 38 that serves as a bearing for the nut 34. Secured to the inner end of the cylindrical bearing 38 is a gear 39. This gear is held against rotation by means of a key 40. A gear 41 is mounted for rotation about the cylindrical bearing 38 and is separated from the latter by a suitable bushing 42 of brass or similar material. The rear end of gear 41 has an outwardly extending flange 43 which is connected with the inwardly extending flange 44 of the cylindrical member 45 by means of rivets 46. Since the part 36 is stationary, gear 39, which is rigidly connected to it, must also be stationary. Located within the cylindrical member 45 is a sleeve 47, whose outer diameter is such that it will fit the inside of member 45 with a pressed fit. Sleeve 47 is thinner on one side than on the other and therefore its inner surface is eccentric with respect to its outer surface, all as shown in Figs. 14, 15 and 16. Secured to the inside of sleeve 47 is a tubular gear 48. This gear is provided on its inner surface with gear teeth 49. The diameter of the tubular gear 48 is such that when the gear teeth of gear 39 are properly meshed on one side, there will be a slight space between the tips of the 130

gear teeth at a diametrically opposite point in the manner shown in Fig. 15. In the example shown gear 39 has 64 teeth while tubular gear 48 has 66 teeth. Gears 48 and 39 form a wobble reduction gear and in order to make them operative, it is necessary that one of these gears shall rotate about the axis of the other in a circular path which is concentric with the axis of the other gear. In order to effect this relative movement of the two gears, the tubular gear has been mounted, as above explained, within the eccentric opening of the tubular sleeve 47. The eccentricity of the opening in this sleeve is slightly greater than the depth of the teeth, so that the gears will always maintain the relative position shown in Fig. 15 while rotating at different speeds. The sleeve 47 is held in place by friction which is produced by the pressure against its ends due to the clamping action of member 50 when rotated into position in the threaded end of the cylindrical member 45. A lock nut 51 serves to hold member 50 in place. The member designated as 50 is a flange that projects outwardly from the tubular shaft 52. When shaft 52 is rotated by means of power, the assembly comprising member 45 and sleeve 47 rotate as a unit and give to the gear 48 a movement which causes its center to travel in a circle about the center of gear 39, there being of course relative rotation between gear 48 and member 47. Since gear 39 is stationary and has two teeth less than gear 48, a relative rotation will take place between these two gears which in the example shown will result in a gear ratio of 32 to 1. It is now desirable to transmit rotation from gear 48 to nut 34 and this is accomplished by means of the following mechanism. The rear end of the tubular gear 48 is provided with two or more notches 53 which are engaged by projections 54 on the edge of disk 55, and therefore this disk will have the same rotary motion as the tubular gear. A disk which has been indicated by reference numeral 56 is secured to the tubular nut 34 in the manner shown in Fig. 14 and is forced against the shoulder 57 by means of a tubular nut 58 that is threadedly connected with the rear end of nut 34 and is held in place by means of a lock nut 59. The disk 56 is held against rotation by means of the friction produced by the clamping nut and also by means of one or more keys 60. The rear surface of disk 56 is provided with two diametrical ribs 61 that correspond to similar diametrical ribs 62 on disk 55. Separating disks 55 and 56 and serving to transmit motion between the two is a third disk which has been designated by reference numeral 63. This disk is provided with diametrical grooves 64 on the side adjacent disk 56 and these grooves are adapted to receive the ribs 61 and on the opposite side disk 63 is provided with similar grooves 64a which are located at right angles with respect

to the groove 64 and these grooves are adapted to receive the ribs 62 of disk 55. The three disks 55, 56 and 63 form a coupling by means of which motion can be transmitted between two members that rotate on parallel but non-aligned axes. When the tubular gear 48 is rotated, it will impart its rotation to disk 55 and this in turn will transmit the motion to disk 56 through the intermediary of disk 63. As disks 55 and 63 have a wobble motion with respect to the center of the tubular nut 58, the openings through which the tubular nut extends must be larger in diameter than the outside diameter of the cylindrical portion of this nut so as to permit the proper movements without binding.

With the gear mechanism just described, when the tubular shaft 52 is rotated by means which will hereinafter be more fully explained, it will cause the tubular gear 48 to have a wobble motion about gear 39 and to travel at a speed that is greatly reduced in comparison with the speed at which shaft 52 rotates, and this reduced speed is transmitted to the tubular nut 34 by the mechanism above described and this nut therefore rotates at a comparatively slow speed and moves the bar 32 in a direction corresponding with the direction in which the parts rotate. The parts just described are enclosed in a casing formed in part by a cylindrical casing member 31 which has a part 66 of increased diameter that encloses the rear end of the cylindrical member 45. The outer flange 67 of the part 66 has secured to it a bearing 27 whose other side is secured to the stationary member 36. This bearing carries the shaft 26 on the inner end of which is secured the bevelled gear 68 that cooperates with the gear 41 and therefore when the latter rotates, it will also rotate the shafts 26 and 23 and thereby rotate the screws 17. The gear ratios are calculated in such a manner that the longitudinal movement imparted to bar 32 by the rotation of nut 34 is the same as the forward movement imparted to the lower end of the shield by means of screws 17 and the nuts carried by the shield, and therefore the shield will be moved with respect to the frame in such a manner that the two will always remain parallel.

Secured to the rear end of cylindrical member 31 is a cap 69 which has an opening provided with a spherically curved inner surface 70 with which the spherical surface of the enlarged inner end 71 of the tubular member 72 cooperates. A bushing 73 is secured to the inner surface of the rear end of member 31 and serves as a bearing for the coupling member 74 to the inner surface of which shaft 52 is connected. This coupling member has an opening in its rear end that is provided with spherically curved surfaces 75 for the reception of the ball 76, on the end of shaft 77. Pins or trunnions 78 extend in

diametrically opposite directions from the spherical member 76 and engage in recesses or notches 79 in the end of member 74. This produces a universal coupling that permits power to be transmitted from the shaft 77 to the tubular shaft 52 even if the axes of these shafts are not in alignment. The tubular member 72 has lugs 80 that engage in notches in the housing 31 so as to prevent this member from rotating. Referring now more particularly to Fig. 1 it will be seen that the tubular member 72 extends to and is connected with the reduction gear casing 81 on the end of the drive motor 82. Since member 72 cannot rotate and since it is connected to the gear casing by bolts or screws 83, it prevents the motor from rotating about its support when it is exerting the torque necessary to operate the device. Shaft 77 is provided with a worm 84 that engages a worm wheel 85 which is mounted on a shaft that extends to the outside of this casing and which carries a bevel gear 86 that cooperates with a similar gear 87 on one end of the extension shaft 88. The lower end of this shaft is connected by means of two bevel gears 89 with the end roller of a belt conveyor which has been indicated in a general way by reference numeral 90. This conveyor will be referred to hereinafter. Referring now to Fig. 1 it will be seen that the shield 3 is provided with a widened portion 91 at its upper end which serves to hold the ground in place during the introduction of the concrete.

With the parts assembled in the manner above described, the operation of the machine will now be described. The shield and frame being assembled as above are telescoped so that the shield is in the position shown by dot and dash lines in Fig. 1. Before the machine is introduced, the tunnel should be started so as to have a suitable sized opening in which to place the parts. After the machine has been put in place a preformed concrete base member 92, that will be herein-after more fully described, is put into position directly back of the frame after which two form members 93 are put into place directly above the concrete block. These form members are curved to correspond with the curvature of the finished opening as shown in Figs. 1 and 7 and are provided at their upper ends with lugs 94 that cooperate to form a dovetail shaped lug having two inclined sides 95. A slidable latching device comprising bars 96 and 97 is attached to these lugs in the manner shown in Fig. 7 and serves to hold the upper ends in aligned position. The lower ends are anchored to the blocks 92 by means of wires moulded in these blocks. The forms 93 are made of sheet steel and have their edges reenforced by angle irons 98 in the manner shown in Fig. 8. When the form members have been put into place, concrete mixture is introduced by

means of a pneumatic device which has been shown by dotted lines in Fig. 1. In making the first concrete section, it is, of course, necessary to provide a wall at the rear of the forms, but after the first section has been poured, the front surface of the form and the retaining plates will form an abutment wall for the next section. When the space between the forms and the wall of the shield has been filled with concrete until the upper surface is substantially along line 99, retaining plates are taken from the last moulded section and inserted between the frame and the concrete. These retaining plates have been shown in Figs. 7 and 8 where they have been designated by reference numeral 100. There are several sections of retaining plates of such size and shape that they extend from the front edge of the forms to the inside of the shield and from the top of member 20 to the top of concrete base members 92. Each plate has one edge reenforced by means of a casting 101 to which the curved latch bar 102 is pivotally attached. This casting is provided with lugs 103 that have openings which serve as bearings for the ends of this bar. A hook 104 is pivotally attached to the center of the latching bar and the latter is provided with a handle 105 by means of which it can be rotated. The forms 93 are provided with depressed surfaces 106 which permit the hook to be inserted thereinto so as to engage the inner surface of the angle iron in the manner shown in Fig. 8. Castings 101 are specially constructed and have one flange much wider than the other and this flange, which has been designated by reference numeral 107, projects over onto the outer surface of the form 93 with which it is connected and therefore when the parts are assembled as shown in Fig. 8 the retaining plate will be held rigidly in such a way that they make an angle of substantially ninety degrees with the forms and hold the soft concrete in place while the frame is moved. In order to assure that there will always be sufficient space between the ends of the forms and the frame to permit the retaining plates to be inserted, spacers 108 are employed at predetermined positions. After the retaining plates have been put into place in the manner above described, shaft 78 is rotated in such a direction as to move the shield forwardly. During this part of the operation the ground must be removed and the tunnel lengthened. After the shield has been moved forwardly, the width of another set of forms, the rotation of the screws is reversed and the frame moved forwardly until the space between it and the retaining plates is wide enough to take care of another set of forms, which are then put in position in the manner above described and connected at the top by means of the latching bars 96 and 97 and at their bottoms to a block 92. When a sufficient number of sections

have thus been formed, the motor 82 is attached to the lugs 94 of some of the sections by means of a dovetailed slide 109. When the tunnel is first started the motor is supported 5 on a temporary support.

The slideable latching bars have been shown in Figs. 9 and 10, from which it will be seen that member 96 is provided with spaced curved slots 110 and that member 97 has rivets 111 that extend through these slots, and therefore when the two bars are moved relative to each other, the flanges 112 will move towards or away from each other, depending upon the direction in which the bars move. 10 Secured to the end of bar 97 is a handle 113, which is pivoted at 114. This handle has a projection 115 which is perforated for the reception of a rivet 116, a connecting rod 117 has one end provided with an opening for the 15 rivet 116 and the other one connected to the bar 96 by means of the rivet 118. It is apparent that by rotating the lever 113, bars 96 and 97 can be moved relative to each other. When the parts are in the position shown in 20 Fig. 9, the connecting rod 117 and the part 115 form a toggle which is slightly overset and which therefore locks the bars in adjusted position. In order to align the parts with the frame, the latter has been provided 25 with a lug 119 with which the forward ends of the latching bars are engaged in the manner shown most clearly in Figs. 5 and 6.

After several sections have been formed, so that all the parts will be in the position 30 shown in Fig. 1, the forms will provide a solid abutment which will resist the pressure exerted thereon when the shield is moved forwardly by the action of the screws that have been above described. When the shield is 35 moved forwardly it is of course necessary to remove the dirt at the inner end of the tunnel and this can be readily done by a man using a pick or a hoe, and when the dirt is loosened it is scraped onto the conveyor by 40 means of a hoe or other suitable tool and is elevated into the dump car 120. The conveyor is provided with a truck having wheels 45 121 by which it is supported on a track formed by ledges that are provided for this 50 purpose on blocks 92. As the specific construction of the conveyor is not claimed in this application, it will not be described in detail and has been shown more or less diagrammatically in Fig. 12 merely for the purpose of facilitating the description. The 55 conveyor, however, forms a part of the machine and cooperates to produce the desired result, and, therefore, it is an element of the combination which forms the subject of this 60 invention.

It is obvious that in order to make it convenient to remove the muck from the inner end of the tunnel, the frame must have an unobstructed opening through which the 65 muck can be removed and which will permit

a man to operate without undue hindrance. Attention is called to Figs. 2 and 3 from which it will be seen that the frame is so constructed that it has a clear opening in its center and that it is therefore especially well 70 adapted for this purpose as it permits the free use of any tools necessary to break down the material and to transfer them onto the conveyor. The lower end of the frame is open so that the frame will yield somewhat 75 and prevent binding in the shield if the latter is slightly deformed by pressure.

Since the concrete has to be introduced from the front end of the mould and at the top, it is essential that a suitable device shall 80 be provided for elevating the concrete and for discharging it into the upper end of the form. Such a device has been shown by dotted lines in Fig. 1 and consists of a hopper 122 in which the grout is placed and which 85 is provided with a pipe 123 that extends upwardly through the upper part of the form. Compressed air is applied to the upper surface of the concrete grout through a pipe or tube 124 and the concrete is therefore transferred 90 by the pneumatic pressure. After each section has been poured and the retaining plates put into position, the motor is started for the purpose of advancing the 95 shield and when this has been advanced, the motor is reversed so as to move the frame forwardly in order to permit another section of 100 form to be put in place. The tunnel is thus advanced, one section at a time, and lined with concrete as it advances and therefore 105 it is possible to build a tunnel in sand or loose dirt without cutting through from the top as is now customary. By means of this machine tunnels can be cut under streets without interfering with the traffic and can 110 be cut in any place without making it necessary to employ timbering or other expensive and difficult means for supporting the ground until the lining is put in place.

By loosening bolts 14 the tubular members 110 115 18 can be independently rotated so as to permit the shield and frame to be adjusted with respect to each other.

I desire to call attention, at this point, to the construction of the blocks 92 which are 115 premoulded and put into place at the rear of the form when the latter has been moved forwardly. The shape of these blocks can be seen by referring to Figs. 1 and 2. From Fig. 2 it will be seen that each block has a 120 transverse lug 125 near each end. The upper surfaces of these lugs form a track on which the conveyor may travel and which also serve as a track for the car 120. By the simple expedient of providing the blocks with 125 these integral lugs the track is built as fast as the tunnel is extended inwardly. Blocks 92 are also provided with reenforcing wires 126 whose free ends are employed to secure the lower ends of the forms and to hold them 130

from inward movement. By employing the retaining plates to hold the wet grout while the frame is moved and until another section has been poured, it is possible to build the tunnel fast as it is not necessary to wait for the cement to set. The forms cannot be removed until the cement has set, but by using a sufficient number of forms it is possible to leave them in place as long as may be necessary.

The conveyor is pivoted at 127 to the upper ends of the frame members 128 that are in turn pivoted to the truck at 129, and is held in the position shown in Fig. 12 by means of a latching member 130. When the latch is released the conveyor and frame 128 are moved in a counter-clockwise direction until the conveyor assumes the position indicated by dotted lines in Fig. 12 and this makes it possible to pass the cement introducing device, shown by dotted lines in Fig. 1, over the top of the conveyor when the cement is to be poured. The distance between the outside of wheels 120 being less than the distance between the inside of the wheels of the cement pouring apparatus as shown in Fig. 18.

The tunneling machine just described finds its greatest field in connection with the construction of tunnels or openings of all kinds through soft dirt, sand or wash formations where the character of the soil is such that it requires support, as by using this machine the need of timbering or other artificial support is obviated, thereby reducing the cost of the construction.

I want to call attention at this point to the fact that the distance between the outside of the form and the inside of the shield increases quite fast towards the top. The reason why I provide so much more space at the top is that it sometimes happens that boulders are removed that leave a recess of considerable capacity on the outside of the shield, and, therefore, when the shield is moved forward the concrete will flow into this cavity, and unless a sufficient reserve of cement is provided at the top, the crown of the lining will be greatly weakened. When the tunnel is constructed in ground that needs support, the top of the tunnel opening will cave in as soon as the shield is moved forwardly, and it is, therefore, impossible to add concrete to replace that which is used to fill cavities into which the cement flows when the shield is moved.

In the specifications and claims the statement is made that the frame is of a size and shape to fit the inside of the shield. This is not to be understood as meaning that the frame fills the shield completely as the frame is separated from the shield, both at the top and at the bottom. It is sufficient if the sides of the frame fit the inside of the shield, as it is only where the frame serves to retain the

concrete that it needs to fit against the surface of the shield.

Having described the invention what is claimed as new is:

1. A tunneling machine comprising, in combination, a tubular shield of the size and shape desired for the unfinished tunnel, a frame of the proper size and shape to fit the inside of the shield, said frame having an opening therethrough, a plurality of threaded screws extending between and connecting the frame and shield, a nut for each screw, said nuts being rotatably connected with one of said members, and means for producing simultaneous and equal rotation between the nuts and the screws whereby the frame and shield will move relative to each other. 70 75

2. A tunneling machine comprising, in combination, a tubular shield of the size and shape desired for the unfinished tunnel, an open frame whose outside size and shape is such that it will fit the inside of the shield, a plurality of screws connecting the frame with the shield at spaced points, a nut associated with each screw, and means for producing simultaneous relative rotation between the nuts and screws whereby the frame and shield will be moved relative to each other. 80 85

3. A tunneling machine comprising, in combination, a hollow shield, reinforcing members along the front edge of the shield, a frame slidable in the shield, said frame having an opening, a gear casing connected with the frame near the upper end thereof, a plurality of screws connecting the frame and the shield and connected with both, a nut forming one connection for each screw, and means for effecting simultaneous relative rotation between the nuts and screws, said means being connected with the gear casing. 90 95 100 105

4. A tunneling machine comprising, in combination, a shield of the size and shape of the unfinished tunnel, a frame of the size and shape to fit the inside of the shield, a plurality of nuts secured to the front edge of the shield, a screw connected with each nut, one end of each of the screws being connected with the frame, means for simultaneously rotating the several screws whereby the frame and shield can be moved relative to each other, a pair of form members adapted to be placed directly to the rear of the frame, means for connecting the upper ends of the form members, retaining plates adapted to be inserted between the frame and the form members, and means for latching the plates to the forms. 110 115 120

5. A tunneling machine comprising, in combination, a shield of the size and shape of the unfinished tunnel opening, a frame of the size and shape of the interior of the shield, said frame having an unobstructed central opening through which the muck may be removed, a plurality of spaced propelling 125 130

- 5 screws for interconnecting the frame and shield, one of said members having nuts with which the screws cooperate, means for producing simultaneous relative rotation between the screws and the nuts, and means for independently adjusting the screws and nuts.
6. A tunneling machine comprising, in combination, a shield of the size and shape of the unfinished tunnel, the upper end of the shield having a widened portion, a frame of the size and shape to fit the opening in the shield, the center of the frame being open, a plurality of screws extending between the frame and the shield, nuts carried by one of the members, the screws being connected with the nuts and with the other member, and means for producing simultaneous relative rotation between the nuts and screws.
7. A tunneling machine, comprising, in combination, a shield of oval shape and of the size of the unfinished tunnel opening, the shield having a reenforcing member on its inner surface adjacent the front end, the upper ends of the reenforcing member being connected with a transverse bar located near the top of the shield, an open frame located in the shield and movable therealong, a threaded bar having one end connected with the transverse bar and the other extending through an opening in the frame, a nut rotatably connected with the frame and operatively associated with the threaded bar, a plurality of nuts secured to the inside of the shield near the front end thereof, a screw operatively associated with each nut, one end of each screw being rotatably connected to the frame, and means for simultaneously rotating the nut that is carried by the frame and the screws.
8. A tunneling machine comprising, in combination, a tubular shield, a frame located in the shield and movable therealong, a plurality of screws extending from the frame to the shield, a nut associated with each screw, a motor for rotating the nuts and screws relative to each other and a reduction gear between the motor and the screws.
9. A tunneling machine having a shield of the size and shape of the unfinished tunnel opening, an open frame of the size and shape of the inside of the shield, means for producing relative movement between the shield and frame, a sectional form adapted to be put into place adjacent to the rear surface of the frame for forming therewith a chamber adapted to receive and hold a cement grout, and retaining plates adapted to be inserted between the frame and the adjacent edge of the form for retaining the grout when the frame is moved forwardly.
10. A tunneling machine having a shield of the size and shape of the unfinished tunnel opening, an open frame of the size and shape of the inside of the shield, means for producing relative movement between the
- shield and frame, a sectional form adapted to be put into place adjacent to the rear surface of the frame for forming therewith a chamber adapted to receive and hold a cement grout, retaining plates adapted to be inserted between the frame and the adjacent edge of the form for retaining the grout when the frame is moved forwardly, and latching means for securing the retaining plates to the forms.
11. A tunneling machine having a shield of the size and shape of the unfinished tunnel opening, an open frame of the size and shape of the inside of the shield, means for producing relative movement between the shield and frame, said last named means comprising a plurality of screws that extend from the front edge of the shield to the frame, nuts secured to one of the members for cooperating with the screws, and means for simultaneously rotating the nuts and screws relative to each other, said means comprising a bevel gear located near the top of the frame, a bevel pinion located on each side of the first gear, a shaft extending downwardly from each of the two pinions, and means interposed between the shafts and the screws for producing relative rotation between the screws and nuts.
12. A tunneling machine comprising, in combination, a shield of the size and shape of the unfinished tunnel opening, a frame movable in the shield, said frame being open from the inner lower end and upwardly, a plurality of screws connected with the frame and the shield, one of said members having nuts that cooperate with the screws and means for simultaneously rotating the screws and the nuts relative to each other whereby the frame and shield will be moved relative to each other.
13. In a device of the class described, a set of tunnel forms comprising, in combination, a tubular shield, a correspondingly shaped frame located within the shield, said frame being open from the bottom upwardly, means comprising a plurality of internally threaded members and screws for movably interconnecting the frame and shield, and means for simultaneously rotating the screws and internally threaded members relative to each other, whereby the frame and shield will be moved relative to each other.
14. A tunneling device comprising, in combination, a shield having the size and shape of the unfinished opening, a frame of the proper size and shape to fit the inside of the shield, means for moving the frame and shield relative to each other, a plurality of pairs of form sections located to the rear of the shield and frame, means comprising a motor for operating the moving means, and means for slidably supporting the motor from the top of the form sections.

15. A tunneling device comprising, in combination, a shield having the size and shape of the unfinished opening, a frame of the proper size and shape to fit the inside of
5 the shield, means for moving the frame and shield relative to each other, a plurality of pairs of form sections located to the rear of the shield and frame, means comprising a motor for operating the moving means and
10 means for supporting the motor from the form sections.

In testimony whereof I affix my signature.
